UNITED STATES PATENT OFFICE.

SANDERS M. THAYER, OF JAMESTOWN, NEW YORK.

ROAD-SCRAPER.

SPECIFICATION forming part of Letters Patent No. 545,748, dated September 3, 1895.

Application filed February 6, 1895. Serial No. 537,413. (No model.)

To all whom it may concern:

Be it known that I, SANDERS M. THAYER, a citizen of the United States, residing in Jamestown, in the county of Chautauqua and State of New York, have invented certain new and useful Improvements in Road-Scrapers; and I hereby declare that the following is a full and exact description of the invention, which will enable others skilled in the art to which it appertains to make and use the same.

The object of my invention is, first, to make a self-dumping scraper; second, one that will better gather all the earth in the path of the scraper; third, one that will take larger loads and better smooth off the load being dumped, and the improvements consist in enlarging the main body of the scraper, making the front edge of the blade straight, or nearly so, letting the sides come as high at the front end 15 as the rear, and also in providing the same with a self-dumping device, all of which will be readily understood by this specification and the accompanying drawings, in which—

Figure 1 is a perspective view of a scraper embodying my invention. Fig. 2 is a plan view of the rear end. Fig. 3 is a plan view of the scraper. Fig. 4 is a side elevation of the scraper being dumped.

In the drawings, A is the blade of my scraper, 30 made preferably of steel; but other suitable materials may be used. This blade is straight, or nearly so, along the lower front edge, the sides coming up on a sharp angle to the height of the scraper-body, and the edge is rolled 35 over, as shown at a, to stiffen it and also to protect the dumping device and form a wearing-surface. The lower corners of the blade may be at nearly right angles, as shown; but I prefer to have them rounded, as it makes 40 the blade stronger.

a' is the back or end of the scraper, and I generally make this of hard-wood plank, to better secure the sides, handles, and dumping apparatus.

45 B is the drawing-bail, and this I always hang on the inside, as at b, and this I find an advantage in loading, the earth following the bail into the scraper much better than where the bail is hung from the outside.

50 D D are the handles for the scraper, which may be secured in any suitable manner. I generally secure them to the back of the

scraper by heavy iron straps secured to the back and turned to pass along the upper and lower edge of the handles and securely bolted or riveted thereto. The dumping device consists in taking a heavy iron rod, bending it in the center to form the loop c, or a piece may be welded or clipped on in place of loop, then bending each arm outwardly to pass the back 55 of the scraper, then turning each at right angles inwardly and parallel to pass along the sides of the blade, and bending the points down, as shown at c'. This rod C is properly secured to the rear of the scraper and is held 60 up under the edge of the blade a by a spring-latch f and f', which may be of any suitable form to hold the dumping-rod in position and allow a throw-off.

E is a strong rod passing preferably 70 through the blade of the scraper at the rear edge and serving to hold the scraper together, and has its ends pass enough beyond the sides of the scraper to act as a stop, as shown in Fig. 4; but this rod is not essential to the 75 successful working of my scraper, as other stops might be used and other means employed to hold the rear end of the scraper securely together.

The operation is as follows: The scraper is 80 loaded in the usual way, only that it takes clean all earth in its path till the scraper is full, and the front sides being as high as the rear the dirt stays in the scraper and does not roll off and leave ridges each side, as with the 85 common scraper. When hauled to the place of unloading, the trip f or f' is touched by the foot of the driver, the front ends of dumping-rods fall and engage the ground, causing the rear of the scraper to be hoisted high enough 90 so that by the team moving forward the scraper is turned over, and the dumping-rod falls back to place and is held securely in position by the latch f ready for the next operation. It will be readily understood that by 95 having the lower edge of scraper straight the dump can easily be kept smooth.

Having fully described my invention, what I claim as new, and desire to secure by Letters Patent, is—

1. In road or earth scrapers, the blade having its upper line of sides (a little back from the lower edge) in a line parallel or nearly parallel to the lower line of said sides, the up-

per edge of the blade being turned over to stiffen the sides of the scraper substantially as shown and described and for the purpose set forth.

5 2. In earth or drag scrapers, the body of the scraper formed as shown, having a draw bail connected to the scraper on the inside, a dumping rod encircling the rear of the scraper, a throw off for said rod, so the front ends of the 10 rod will engage the earth to dump the scraper, in combination with stops rigidly secured to the body of the scraper, to prevent the dumping rod moving too far back, substantially as shown and for the purpose set forth.

3. In road or earth scrapers the blade A. 15 provided with sides a. and back a'. bail B. hinged inside the blade, the scraper being provided with handles D. D. in combination with dumping rod C. having loop F. and a suitable tripping device substantially as shown 20 and described and for the purpose set forth.

In testimony that I claim the foregoing I subscribe my name in the presence of two witnesses.

SANDERS M. THAYER.

Witnesses:

S. A. BALDWIN,
MILo HARRIS.
